COMBINED HEADBOARD AND CHEST UNIT

Roland Carter, New York, N.Y., and Jean P. Giacomini, York, Pa., assignors to Thonet Industries, Inc., New York, N.Y., a corporation of Delaware

Application June 26, 1957, Serial No. 46,748

Term of patent 3½ years

(Cl. D5—4)

Fig. 1 is a front perspective view of a combined headboard and chest unit showing our new design.

Fig. 2 is an enlarged detail of a section taken on line 2—2 of Fig. 1.

Fig. 3 is a fragmentary rear perspective view of one end portion of the headboard and the chest unit as viewed oppositely to that shown in Fig. 1.

We claim:

The ornamental design for a combined headboard and chest unit, as shown.
